UNITED STATES PATENT OFFICE.

MARK LAMPMAN PIKE, OF ST. PAUL, MINNESOTA, ASSIGNOR OF ONE-THIRD TO CHARLES F. TIEDMAN AND ONE-THIRD TO RICHARD ERICKSON, BOTH OF ST. PAUL, MINNESOTA.

CALCULATOR.

Application filed June 15, 1922. Serial No. 568,384.

To all whom it may concern:

Be it known that I, MARK LAMPMAN PIKE, a citizen of the United States, residing at St. Paul, in the county of Ramsey and State of Minnesota, have invented a new and useful Calculator, of which the following is a specification.

My invention relates to improvements in calculators.

- 10 Its object is to provide a simple and efficient device adapted particularly, though not exclusively, for quickly and easily computing amounts representing wages at different scales for different periods of time.
- 15 With the foregoing and other objects in view, which will appear in the following description, the invention resides in the novel combination and arrangement of parts and in the details of construction herein-
20 after described and claimed.

In the drawings, Figs. 1 and 2 are plan views of a device embodying my invention, the slide-rest and the slide being shown in different positions; Fig. 3 is a sectional view
25 taken on the line 3—3 of Fig. 1 and Fig. 4 is a similar view taken on the line 4—4 of Fig. 1.

Referring to the drawings, 10 indicates a table having grooves 11 in its longitudinal edges and a schedule on the face thereof consisting of columns of numbers A and B. A frame X, traversing the table 10, includes a pair of blocks 12, one for each side of the table, each block having a tongue 13 formed thereon and adapted to slide in a groove 11 in said table. Said frame also includes a slide-rest 14, which is secured at its ends to the blocks 12. The frame X is equipped with a fixed indicator and movable indicator, the former comprising a window 15 in said frame, said window being designed to register singly with the numbers in the column A. The movable indicator comprises a slide 16 fitted with beveled edges 17 and slidably retained thereby in a way 18 in the slide-rest 14, said slide being formed with a window 19 designed to register singly with the numbers in each of the columns of figures B. A slot 20 in the slide 16 and a slot 21 in the slide-rest 14 register respectively with the windows 15 and 19 in all of the operative positions of said slide 16. The numbers in the column

A represent periods of time progressing by half hours from top to bottom of said column, the letters "hrs." appearing on the slide-rest 14, as at 22, and in line with said column of figures A to designate the same as indicative of time. Each number in each column B indicates an amount payable at a given rate for a given time represented in hours by a certain number in the column A. Guides consisting of figures, indicating different rates or scales of wages per hour appear, as at g, on the slide rest 14, each guide being arranged in line with its respective column of figures B. The numbers in the columns A and B are arranged with respect to each other so that when a certain number, indicative of time, is visible through the window 15, a number indicative of the amount payable will be visible through the window 19, following the alignment of said window with the guide g indicating the rate upon which the amount payable is based. Thus, as in Fig. 1, three hours, (the figure 3 being visible through window 15) at 40¢ per hour amounts to one dollar and twenty cents (1.20 being visible through the window 19). Also, as in Fig. 2, five hours at 75

claim as new and desire to protect by Letters Patent is:

1. In a calculator, a table and a frame, one being movable with respect to the other, 5 said table bearing series of symbols, an indicator associated with said frame and adapted to selectively indicate each symbol of one of said series, and a second indicator movable with respect to said frame and 10 adapted to selectively indicate each symbol of each of the other series relating to the selected symbol of said first series.
2. In a calculator, a table, a slide-rest mounted on said table and adapted to move 15 longitudinally thereof, said table bearing a series of symbols indicative of multipliers and other series of symbols indicative of products, said slide-rest having symbols thereon indicative of multiplicands and 20 also having a window therein adapted to be selectively registered with each multiplier, and a slide on the slide-rest having a window therein adapted to be selectively

aligned with each multiplicand and to register with the symbol indicative of the 25 product of the selected multiplier and multiplicand.

3. In a calculator, a table and slide-rest, one being movable with respect to the other, 30 said table bearing a series of symbols indicative of multipliers and other series of symbols indicative of products, said slide-rest having symbols thereon indicative of multiplicands, an indicator associated with the slide-rest and adapted to be selectively 35 positioned with respect to each multiplier, a slide on the slide-rest, an indicator associated with said slide and adapted to be selectively positioned with respect to each multiplicand and to designate the symbol 40 indicative of the product of the selected multiplier and multiplicand.

In testimony whereof, I have signed my name to this specification.

MARK LAMPMAN PIKE.
